A copy of the original application for a patent for an invention, in the name of Nicholas Testi, was filed in this office on May 1, 1939, Serial No. 271,115, and is assigned to Gillette Safety Razor Company, Boston, Mass., a corporation of Delaware.

UNITED STATES PATENT OFFICE

2,213,292

DETACHABLE-BLADE KNIFE

Nicholas Testi, Boston, Mass., assignor to Gillette Safety Razor Company, Boston, Mass., a corporation of Delaware

Application May 1, 1939, Serial No. 271,115

4 Claims. (Cl. 30—156)

This invention relates to knives of general utility designed to employ replaceable safety razor blades as their cutting elements.

In general the objects of the invention are to provide at low cost a thin flat knife convenient to be carried in the pocket of the user and having a handle shaped to support the blade firmly in exposed cutting position or securely in completely guarded position, still permitting the convenient removal of the blade for replacement whenever desired.

To these ends an important feature of the invention consists in a perforated handle in combination with a spring clip having arms for engaging opposite sides of the handle. One arm of the clip is equipped with a fulcrum pin shaped to engage the blade through the perforation of the handle and the other arm shaped to co-operate with the handle as a retainer for the knife as a whole. Means are provided between the handle and the clip for positively holding the clip from slipping off the handle while permitting sufficient movement thereof to disengage the blade. For example, as herein shown the clip is connected to the handle by a pin which positively engages the clip with a clearance sufficient to permit the fulcrum pin to be retracted and moved out of registration with the perforation in the handle of the knife. When the clip is so positioned the blade may be freely withdrawn or replaced and when once replaced the clip may be restored to its operative position in which the fulcrum pin enters the handle and passes through a suitable perforation in the blade. The fulcrum pin not only co-operates to support the blade firmly in cutting position but serves as an axis about which it may be swung for movement into and out of guarded position.

These and other features of the invention will be best understood and appreciated from the following description of two preferred embodiments thereof selected for purposes of illustration and shown in the accompanying drawing, in which:

Fig. 1 is a view in elevation of a complete knife exemplifying one embodiment of the invention;

Fig. 2 is a fragmentary view of the same knife showing the blade moved partially to its guarded position;

Fig. 3 is a view in perspective of the handle or holder;

Fig. 4 is a view in perspective of the clip member;

Fig. 5 is a plan view of a blade of one type suitable for use in the knife;

Fig. 6 is a view in elevation of a knife exemplifying another embodiment of the invention;

Fig. 7 is a similar view of the same knife with its blade in guarded position; and

Fig. 8 is a view on a smaller scale of the same knife showing the clip in blade disengaging position.

The handle or holder 10 of the knife shown in Figs. 1 and 2 comprises a sheet metal blank folded upon a longitudinal axis and is of a width 10 when folded slightly greater than that of the blade it is to contain. The blank may be provided with an embossed area 11 of ornamental contour which is effective not only to stiffen the handle but to provide clearance for the corner 15 of the blade as the latter is swung from cutting to guarded position as will presently appear. The handle is provided in its free edge with an elongated recess 12 in which the cutting edge of the blade is exposed. It is also provided, as best shown in Fig. 3, with a fulcrum pin hole 13 disposed approximately centrally in the handle and extending through both of its sides. In line with this hole and near one end the holder is provided on one face with a pair of short projecting pins 14 and 15. At the inner end of the blade-exposing recess 12 the walls of the handle are slightly flared to facilitate the introduction of the end of a blade between the two side walls of the handle. The handle may be constructed of sheet steel or other metal which is resilient so that its two side walls may be made normally to engage each other or an interposed blade as the case may be.

Co-operating with the handle 10 is a separate detachable forked clip having a flat body portion 20 and an oppositely disposed tongue 21. The clip is also of resilient metal and the tongue 21 is normally engaged with the body portion thereof. The body portion 20 is provided at its outer end with a fulcrum pin 22 of such diameter as completely to fill the fulcrum pin hole 13 of the handle and of such length as to extend entirely through both sides of the handle. The body of the clip is also provided with a pair of spaced holes 23 and 24 and is connected to the tongue by a perforated loop which clears the end of the handle when the clip is assembled thereon as shown in Figs. 1 and 2. The hole 24 in the clip is shaped and located to fit over the pin 14 of the handle. The hole 23 is of substantially larger diameter and is located in position to receive the pin 15 of the handle with substantial clearance. The arrangement is such that when the outer or free end of the body 20 of the clip is 55

- sprung outwardly sufficiently to disengage the fulcrum pin 22 from the hole 13 in the handle the clip may be then swung to one side or the other about the pin 14 as an axis sufficiently to 5 carry the fulcrum pin 22 out of line with the hole 13, thus leaving the interior of the handle clear for the presentation or removal of the blade while the fulcrum pin 22 is yieldingly pressed against the side face of the handle.
- 10 The handle is adapted to receive any form of blade having a perforation located near one end in conventional relation to its cutting edge. A suitable blade 18 of the Gillette double-edged type is shown in Fig. 5. This is provided with 15 a centrally disposed elongated perforation having enlargements 19 at each end which thus supply the necessary perforations to receive the fulcrum pin 22. When the clip has been displaced to hold the fulcrum pin 22 in an inoperative 20 position the blade 18 may be presented endwise between the flaring portions 16 of the handle and advanced until one of the enlargements 19 registers with the hole 13 of the handle. Then the clip may be rocked transversely and 25 the fulcrum pin 22 permitted to snap into place, whereupon the blade becomes pivotally connected to the handle. The blade may now be swung about the fulcrum pin 22 into cutting position as shown in Fig. 1 wherein one edge rests against 30 and is supported by the fold vertex of the handle and the other edge is exposed for cutting in the recess 12; or the blade may be swung in clockwise direction about the fulcrum pin 22 as suggested in Fig. 2 into a completely guarded position in which the entire cutting edge of the 35 blade lies to the left of the recess 12 being held yieldingly in this position by engagement of the sides of the handle. In its guarded position the unsharpened end portion of the blade extends 40 slightly beyond the end of the handle 10. The user may consequently safely engage this unsharpened portion of the blade when he desires to swing it again into cutting position.
- It will be seen that I have provided a detachable 45 blade knife of three component parts, each adapted for production under favorable manufacturing conditions, and all adapted to be readily assembled. The clip 20—21, moreover, has the double function of retaining the blade in its 50 handle and of retaining the knife as a whole in the pocket of the user.
- In Figs. 6-8 is illustrated, as another embodiment of the invention, a knife including a single-edge blade. In its construction the handle or 55 holder 30 comprises a sheet metal blank folded upon a longitudinal axis and of a width when folded at least equal to that of the blade it is to contain. The blank is provided with a bulged portion 31 in its folded vertex to provide clearance for the corner of the blade as the latter is 60 swung from cutting to guarded position. The handle is cut away to present a curved edge 32 at one end which increases the length of exposed edge when the blade occupies its operative position. The handle is also provided with a fulcrum pin hole 33 located some distance within 65 the curved edge 32 and extending entirely through both sides of the handle. Near its other end, the handle is provided with a short projecting pin 34 for retaining the clip, as will be presently explained, and below the pin 34 in the open edge of the holder is provided a notch 35 through which one corner of the blade may be reached when it is desired to swing the blade into its operative or 70 cutting position. The handle is also provided

at its right-hand end as shown in Figs. 6 and 7 with a perforated eye or loop 37 to which a light chain or cord may be attached if desired.

Co-operating with the handle is a detachable 5 clip having a flat body portion 40 and an oppositely disposed tongue 41. The clip is made of resilient metal and is adapted to be slipped upon the handle and to engage its opposite sides with yielding pressure. The body portion 40 is provided at its outer end with a fulcrum pin 42 of such 10 diameter as completely to fill the fulcrum pin hole 33 in the handle and of such length as to extend entirely through both sides. The body of the clip is provided with a hole 43 arranged to receive with clearance the pin 34 of the handle and to retain the clip in place while permitting it to be rocked transversely sufficiently to disengage the fulcrum pin 42 from the hole 33 when it is desired to hold the fulcrum pin in inoperative position in detaching the blade. The clip is cut away 20 at its fold or bend to receive the projecting eye 37 of the handle and has sufficient clearance so that it may rock slightly upon the end of the handle when released for such movement by the withdrawal of the fulcrum pin 32 from the hole 33. 25

The blade 26 shown in Figs. 6-8 is of the Valet type having a single sharp edge and a flat unsharpened rear edge. The blade is provided near one end with a circular perforation of suitable size to receive the fulcrum pin 42 of the clip. It 30 is also provided in its end edges with recesses setting off projecting lugs 27 by which the blade may be manipulated without danger of cutting. The clip, as before, has the double function of retaining the blade in the handle and of retaining the knife as a whole in the pocket of the 35 user.

When the blade is in operative position as shown in Fig. 6 it is held in place by the fulcrum pin 42 between the sides of the handle 30 and 40 with its rear unsharpened edge in contact with the fold vertex of the handle and the major part of its cutting edge exposed for cutting. The blade may be moved into guarded or inoperative position by merely swinging it in a counter- 45 clockwise direction about the fulcrum pin 42 until it occupies the position shown in Fig. 7. When it is desired to disengage the blade the forward end of the clip 40 may be easily raised sufficiently to disengage the fulcrum pin 42 from the 50 hole 33 and the clip may be rocked to carry the fulcrum pin out of line with the hole and into some such position as suggested in Fig. 8. Thereupon, the blade may be drawn freely out of the handle and replaced with a new sharp blade 55 whenever desired.

Having thus disclosed my invention and described two embodiments thereof for purposes of illustration but not in any limiting sense, I claim as new and desire to secure by Letters 60 Patent:

1. A detachable-blade knife comprising a handle having a hole for a fulcrum pin, a spring clip having arms for engaging opposite sides of the handle, a fulcrum pin projecting from one arm, a perforated blade shaped to swing on said fulcrum pin from guarded to exposed position, and means on the handle for engaging the said arm for adjustably connecting the clip to the handle. 70

2. A detachable-blade knife comprising a handle of sheet metal folded to present opposed sides which are perforated to receive a fulcrum pin, a perforated blade, and a forked removable clip having arms for engaging opposite sides of the 75

handle and a fulcrum pin for pivotally retaining the blade between the sides of the handle with its back in contact with the fold vertex of the handle and its cutting edge exposed, the blade being pivotally movable about the fulcrum pin to concealed position in the handle.

3. A utility knife comprising a handle of sheet metal folded to present opposed sides which are perforated to receive a fulcrum pin and recessed adjacent to one end, a razor blade narrower than the handle and perforated to receive a fulcrum pin, and a forked detachable clip having a fulcrum pin for the blade, means for retaining said clip on the handle with its fulcrum pin in inoper-

ative position to permit removal of the blade or in operative position in which the blade may be moved pivotally on the fulcrum pin from concealed to cutting position or vice-versa.

4. A utility knife comprising a thin flat handle having a hole for a fulcrum pin, a perforated blade, a forked spring clip having arms for engaging opposite sides of the handle, one carrying a fulcrum pin and the other shaped to co-operate with the handle as a retainer for the knife as a whole, and means for positively holding the clip from slipping off the handle while permitting limited displacement thereof.

NICHOLAS TESTI.
